(57) **CLAIM**

The ornamental design for an instrument, as shown and described.

DESCRIPTION

FIG. 1 shows a front, right-hand side perspective view of the instrument;

FIG. 2 shows a front elevation view thereof;

FIG. 3 shows a right-side elevation view thereof; and,

FIG. 4 shows a left-side elevation view thereof.

The broken lines illustrate portions of the instrument that form no part of the claimed design.

1 Claim, 4 Drawing Sheets
